UNITED STATES PATENT OFFICE.

JAMES B. EADS, OF ST. LOUIS, MISSOURI.

SHIP-RAILWAY CAR AND DRY-DOCK.

SPECIFICATION forming part of Letters Patent No. 239,088, dated March 22, 1881.

Application filed July 12, 1880. (No model.)

To all whom it may concern:

Be it known that I, JAMES B. EADS, of St. Louis, in the State of Missouri, have invented new and useful Improvements in Ship-Railway Cars and Dry-Docks, of which the following is a specification.

The object of my invention is to produce a practical and efficient mode by which a loaded vessel of any size may be docked without danger of injury. To this end I employ a cradle into which a ship may be floated, and which is provided with compound wedges working longitudinally under the keel and transversely beneath the bilge, moved by the pressure of hydraulic jacks, so as to force each wedge firmly home to its bearing while the vessel is afloat. The said wedges are provided with pawls, which hold them securely in the position in which they are set. A uniform bearing is thus provided under all parts of the vessel by causing the supports to adjust and adapt themselves automatically to all parts of the bottom.

The invention further relates to means for conveying loaded vessels indefinite distances overland; and it consists in combining with the aforesaid cradle any necessary number of cars constructed with cross-beams, forming or provided with pedestals, stirrups, and springs, to afford a uniform support to the cradle throughout the length and breadth of the ship, and compensate for the slight irregularities in track.

In order that my invention may be fully understood, I will proceed to describe the mode of carrying it into effect, as illustrated in the accompanying drawings, in which—

Figure 1 is a plan of the docking-basin and adjacent railway-tracks. Fig. 2 is a longitudinal section of the same. Figs. 3, 4, and 5 are transverse sections, on a larger scale, of the dock or basin at different points, indicated by the lines 3, 4, and 5, respectively, in Figs. 1 and 2. Fig. 4 showing an elevation of the cradle without the vessel, and Fig. 5 an outline of the vessel in position. Fig. 6 is a transverse section of the dock on a still larger scale, in the same plane as Fig. 5, showing the cradle also in transverse section. Fig. 7 represents a longitudinal section of a portion of the cradle upon the railway-track. Fig. 8 is a plan of the same. Fig. 9 is a plan of a portion there-

of, on a larger scale, with parts of the bed or body of the car broken away. Fig. 10 is a longitudinal section of the same in the several planes indicated by the irregular line 10 10, Fig. 11, showing a portion of the ship's keel or bottom and the longitudinal wedges for supporting the same in elevation. Fig. 11 is a transverse section of the central portion thereof. Fig. 12 is a detached elevation of one of the bilge-wedges and its operating-jack and retaining-pawl. Fig. 13 is a longitudinal section on the line 13, Fig. 11, representing more clearly the bearing of the keel on the keel-wedges, and showing, also, the actuating-jack and retaining-paws.

Referring to Figs. 1 and 2, A represents a docking-basin with inclined ways of any necessary length to permit the passage of the cradle C under the bottom of a vessel, S, while she is afloat, and the gradual elevation of the same out of the water, after the mode commonly practiced in docking vessels by means of rail-ways. I employ any necessary number of parallel rails R, as shown in Fig. 1, connected with a shifting table, T, having three tracks, R⁴ R⁵ R⁶, or more or less, as preferred, any one of which may be brought into connection with the docking-track R by the lateral movement of the table T, for which purpose the said table is mounted upon suitable wheels and rails.

R⁴ R⁵ R⁶ R⁷ R⁸ represent permanent tracks, with either of which the respective tracks R⁴ R⁵ R⁶ of the shifting table may be brought into connection at will, R⁴ being the main track over which the vessel is to be conveyed, while the others are side tracks, on which cars may be run temporarily with vessels awaiting transportation.

The central part of my cradle C, for any necessary or desirable length, is constructed with elevated sides C', which, extending above the surface of the water, afford platforms on which men may stand for manipulating the connections of the hydraulic jacks (hereinafter described) for the purpose of forcing the wedges to their bearings beneath the bilge and keel of the ship.

For the purpose of illustration, I have indicated at D a steam-pump, at E a pipe for conducting water forced by the said pump, and

at F a hydraulic jack connected with the wedge G, so as to force the said wedge under the bilge of the vessel S.

H, Figs. 10, 11, and 12, are guides controlling the movement of the wedges G upon the bed I beneath the bilge. A jack, F, is provided for each of the wedges G, which are placed at intervals beneath the vessel, from end to end, as illustrated in Figs. 6, 10, 11, 10 and 12, the pipes E being branched so as to connect with the several jacks. Similar branch pipes connect with hydraulic jacks F' to actuate the wedges J, arranged longitudinally beneath the keel of the vessel S at suitable intervals, and bearing on inclined planes or fixed wedges K, as shown in Fig. 13.

L are pawls attached to the several wedges G and J, and engaging in racks M, so as to hold the wedges securely in any position in 20 which they may be set.

The bed I of the cradle C rests, through the medium of springs N, on the bearings O of doubly-flanged wheels P, adapted to run on the rails R.

25 Q are pedestals, operating in the customary manner to preserve the proper relative position of the bed and journal bearings, while permitting the vertical play of the springs N. The cradle-bed is connected to the bearings 30 by stirrups Q', which limit the vertical play of the cradle.

V and U represent, respectively, longitudinal and transverse I-beams or girders, which may be of any proper construction to constitute a staunch and durable frame-work to connect the bearings and preserve the proper relative positions of all parts of the running-gear.

For docking a vessel, the wedges G and J being in their retracted positions, (shown by 40 dotted lines in Figs. 12 and 13,) the cradle C is run out into the position shown at 55 in Figs. 1 and 2, or as far as may be necessary to reach the required depth of water to permit the vessel S to float freely within the cradle without 45 coming in contact with the bearing-wedges G and J. The vessel being brought to rest within the cradle, the operators, by means of the pumps D and jacks F F, drive all the wedges G and J home simultaneously to their respective bearings beneath the keel and bilge of the vessel, so that the ship will now have solid supports, with equal bearing under all parts, determined by the simultaneous movement of

the wedges while she is afloat. The cradle containing the vessel, and supported by its 55 running-gear, being now drawn bodily up the inclined track (shown in Fig. 2) by means of locomotives, will be elevated out of the water without any violence to the ship, and may be transported over the line R⁴ to any distance. When 60 the vessel is to be launched or floated again at the other end of the line the cradle is run down a similar inclined dock until a sufficient depth of water is reached to float the vessel clear of the cradle and permit her to move off. 65 The pawls L are then raised out of the racks M and the respective wedges retracted in readiness for the next vessel. This elevation of the pawls and retraction of the wedges may be readily performed by hand while the cradle is 70 out of the water.

In order to provide for detaching the wedges underneath the water, I have shown, at W, shafts provided with arms connected with the said pawls, so that by turning the said shafts 75 by means of crank-shafts, which may communicate therewith by means of bevel-pinions Y, the said pawls may be simultaneously elevated to permit the retraction of the wedges. This can then be performed by the reverse movement of the jacks, if double jacks be employed; or otherwise, by simple gearing connected with the wedges for the purpose.

It is obvious that the wedges and jacks constituting the first part of my invention are 85 applicable to dry-docks and ordinary marine railways, as well as to railways for conveying vessels over land between navigable waters.

Having thus described my invention, the following is what I claim as new therein and 90 desire to secure by Letters Patent—

1. The combination of the wedges and the hydraulic jacks for setting the wedges up under the keel and bilge of a vessel, substantially as herein described. 95
2. The combination of the wedges G J, jacks F F, and pawls L, substantially as and for the purposes set forth.
3. The combination, in a ship-railway car, of the pedestals Q, springs N, cross-bars U 100 and V, and stirrups Q', substantially as and for the purposes set forth.

JAS. B. EADS.

Witnesses:

OCTAVIUS KNIGHT,
GEO. T. SMALLWOOD, Jr.
